1 Claim. (Cl. 146—279)

1

My invention relates to a machine for cleaning grains, bran and the like, including a beater rotor and a perforated drum.

In machines of this class, such as hulling, husking, decorticating, scouring and polishing machines, it is customary for the purpose of intensifying or attenuating the effect of cleaning to so exchange the rotor drive discs that the rotors rotate at higher or lower speeds as desired. An analogous effect also may be obtained by adjusting the beaters of the rotor relative to the drum, i. e. to vary their spacing from the latter. The said two solutions have the disadvantage that they only may be applied when the machine is out of operation, and that they are complicated and consume much time.

Machines of the class set out are known in the art, in which the rotor and drum are conical and longitudinally displaceable relative to each other so that in operation the clearance between rotor and drum, and thus the effect of cleaning is adjustable. Owing to the unequal diameters, however, the wear and tear is non-uniform and so great that the maintenance of the machine is very expensive.

The machine of my present invention differs from such known machines in that it comprises a tangential inlet and means for adjusting the passage for the goods to be cleaned through the drum during operation of the machine. A further advantage of such tangential inlet arrangement is that the high-speed beater rotor cannot suck any air through the inlet and thus also cannot produce any substantial degree of air compression inside the drum, with the result that a minimum of dust is introduced and deposited in the machine space surrounding the perforated drum. In similar prior-art machines which, however, comprise an axial inlet within the range of the beaters, the latter—as is well known—produce a pronounced suction so that compressed air is blown through the perforated drum into the outside machine space, the walls of which thus soon are covered with dust.

Three forms of my present invention are shown in the accompanying drawings, in which—

Fig. 1 is a longitudinal section of a cleaning machine on the line I—I of Fig. 2,

Fig. 2 is a cross-section on the line II—II of Fig. 1,

Fig. 3 shows a portion of Fig. 1 in a larger scale,

Fig. 4 is a portion of Fig. 2 in a larger scale,

Fig. 5 is a longitudinal section of a second example on the line V—V of Fig. 6,

2

Fig. 6 is a cross-section on the line VI—VI of Fig. 5, and

Fig. 7 is a cross-section of a third example.

A perforated drum 2 is secured to the machine frame 1, and 3 is the beater rotor rotatably mounted in the drum 2 and driven through the belt pulley 4. As shown in Fig. 2, the substantially tangential inlet comprises two sidewalls 5 disposed parallel to the axis of the drum 2, and two baffles 6 intermediate of the sidewalls 5 and pinned to shafts 2. The latter are coupled to each other through arms 8 and a link 9. A U-shaped holder 10 is secured to the latter and accommodates a cylindrical nut 12 in longitudinal slots 11. A regulating spindle 13 is screwed in the nut 12 and may be turned by means of a handwheel 14 (Figs. 3 and 4). As shown in the drawing, the two baffles 6 may be adjusted simultaneously through turning the handwheel 14 so as to adjust the point of entry of the goods into the drum 2 longitudinally of the latter. It, therefore, is possible to change, i. e. lengthen or shorten the passageway of the goods from the inlet down to the outlet 15. It, thus, is possible to adjust the cleaning effect during operation of the machine.

In the example shown in Figs. 5 and 6, a fixed, tangentially arranged inlet 16 is provided in the perforated drum 2. A plurality of baffles 17 are disposed over the entire length of drum 2 inside the latter. The baffles are adjustable from the position shown by the full lines in Fig. 5, into the position shown by the dash-and-dot lines. According to the position of the baffles 17, the goods pass through the drum 2 on a shorter or longer way so that the cleaning effect may be correspondingly regulated.

In Figs. 5 and 6, as a modification an outlet 19 is shown, in which three closure slides 20—22 are arranged in line lengthwise of drum 2. According to which of the said three slides is open, the passageway of the goods through drum 2 will be different so that, also in this manner, the cleaning effect may be adjusted accordingly.

In the examples shown in Figs. 1—6, the drum is closed all around downstream of the inlet portion so that in the drum rear portion the goods rotate practically at the same speed as the beater rotor 3. The beating action of the rotor and the cleaning effect in the said drum portion are substantially reduced therefore. In order to eliminate such disadvantage, the drum 2 in the example shown in Fig. 7 is provided with a bay 23 which extends over its entire length and comprises an impingement face 24. At each revolu-

tion of rotor 3, the goods are flung against the said face 24 through the rotor beaters. The latter subsequently again engage the goods falling back into drum 2 in order to again accelerate the goods and throw the same up against the face 24. In this manner a good cleaning effect is obtained over the entire length of drum 2. At the same time, undesired impurities such as bugs, moths and their eggs, small lumps of earth and the like are disintegrated and thus rendered harmless.

What I claim as new and desire to secure by Letters Patent, is:

In a machine for cleaning or scouring grain, bran or like materials, having a beater rotor mounted on a horizontal axis, a perforated drum surrounding the beater rotor, means forming an inlet passage to admit material tangentially to the perforate drum, said inlet passage including two opposed vertical sidewalls and two baffles mounted for pivoting movement on horizontal axes directed at right angles to the drum axis, a similar vertical edge of each baffle being vertically coextensive with a vertical side wall of the inlet whereby the inlet of material is coextensive axially with one end of the rotor, and actuating means for pivoting the baffles about said horizontal axes to vary the point of downward entry

of the material into said drum axially with respect to said rotor and to permit adjustment of the length of travel of material in said drum.

FRITZ TANNER.
